US00D935625S

(12) United States Design Patent (10) Patent No.: US D935,625 S
(45) Date of Patent: * Nov. 9, 2021

(54) THERAPEUTIC ELASTIC SPORTS TAPE

(71) Applicant: Blacktop Plus, LLC, Carrollton, TX (US)

(72) Inventors: Matthew Hicken, Frisco, TX (US); Christian Hicken, Prosper, TX (US); Nathan Ellison, Cedar Hills, UT (US); Nicholas Hicken, Prosper, TX (US); Steven Silvey, Garland, TX (US)

(73) Assignee: Blacktop Plus, LLC, Carrollton, TX (US)

() Term: 15 Years

(21) Appl. No.: 29/728,388

(22) Filed: Mar. 18, 2020

Related U.S. Application Data

(62) Division of application No. 29/649,123, filed on May 25, 2018, now Pat. No. Des. 890,936.

(57) CLAIM

The ornamental design for a therapeutic elastic sports tape, as shown and described.

DESCRIPTION

FIG. 1 is a perspective view of a therapeutic elastic sports tape;

FIG. 2 is another perspective view in use;

FIG. 3 is a top view of the therapeutic elastic sports tape of FIG. 1;

FIG. 4 is a bottom view thereof with shading for illustrating adhesive;

FIG. 5 is a right side view thereof with the left side view being a mirror image;

FIG. 6 is a front view thereof; and,

FIG. 7 is a back view.

In FIG. 2, the broken line showing of a human body depicts environment that forms no part of the claim.

1 Claim, 3 Drawing Sheets
